(57) **CLAIM**

The ornamental design for a bolt head for lifting clamp, as shown and described.

DESCRIPTION

FIG. 1 is a top perspective view of a bolt head for lifting clamp showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings are for the purpose of illustrating unclaimed portions of the bolt head for lifting clamp and form no part of the claimed design. The dash-dot-dash lines only indicate a border between the claimed and disclaimed parts.
